US0D1079268S

(12) **United States Design Patent** (10) **Patent No.:** **US D1,079,268 S**
(45) **Date of Patent:** **** Jun. 17, 2025**

(54) **ORAL CARE IMPLEMENT**

(71) Applicant: **Colgate-Palmolive Company**, New York, NY (US)
(72) Inventors: **Takahide Okai**, Highland Park, NJ (US); **Brian Bloch**, Hillsborough, NJ (US)

(73) Assignee: **Colgate-Palmolive Company**, New York, NY (US)

(**) Term: **15 Years**

(21) Appl. No.: **29/846,716**

(22) Filed: **Jul. 19, 2022**

Related U.S. Application Data

(62) Division of application No. 29/761,626, filed on Dec. 10, 2020, now Pat. No. Des. 960,582.
(51) **LOC (15) Cl.** **04-02**

Primary Examiner — Tamara L Hahn

(57) **CLAIM**

The ornamental design for an oral care implement, as shown and described.

DESCRIPTION

FIG. 1 is a front perspective view of an oral care implement according to our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the article that form no part of the claimed design.

1 Claim, 4 Drawing Sheets
